UNITED STATES PATENT OFFICE.

JOHN H. TODD, OF ERIE, KANSAS.

BURIAL-RECEPACLE.

No. 908,628.

Specification of Letters Patent.

Patented Jan. 5, 1909.

Application filed November 29, 1907. Serial No. 404,198.

To all whom it may concern:

Be it known that I, JOHN H. TODD, a citizen of the United States, residing at Erie, in the county of Neosho and State of Kansas, have invented certain new and useful Improvements in Burial - Receptacles, of which the following is a specification, reference being had to the accompanying drawings.

10 My invention relates to improvements in burial receptacles, and particularly to receptacles of this character made of reinforced cementitious material; and an object of my invention is to provide a receptacle 15 of this character which will combine lightness with great strength and which will be susceptible of being hermetically sealed.

In the drawings illustrating the principle 20 of my invention and the best mode now known to me of applying that principle, Figure 1 is a side elevation of a burial receptacle embodying my invention; Fig. 2 is a longitudinal central section, parts of the wall being broken away to show the construction thereof; Fig. 3 is a transverse section on the line A—A of Fig. 2; Fig. 4 is a detail showing in perspective the steel basket; and Fig. 5 is a sectional detail showing the mode of connection of the handles.

30 The walls of my new burial receptacle are made of a mixture of Portland cement and sand in such proportions as to produce a cementitious material having the requisite strength for the purpose intended. This 35 cementitious material *a* is reinforced by woven-wire netting. This wire netting is woven into the shape which it is intended that the receptacle shall have. There are two such woven-wire shapes *b*, *c* one of 40 which is smaller than and fits within the other. Between the woven-wire shapes *b*, *c* is interposed a layer of cementitious material and within the inner or smaller wire shape *b* and outside of the larger and outer 45 wire shape *c* are placed still other layers of cementitious material. The receptacle thus far constructed is placed within the steel basket shown in Fig. 4. The steel basket is made up of a frame *d* which extends 50 along the side walls and end walls of the receptacle at about the height of the handles.

To the frame *d* are secured U-shaped bands *e* sufficient in number to give the requisite strength. Firmly fastened to the steel basket 55 at the junction of the U-shaped bands *e* with the side bands of the frame *d* are the

handle-bars *f* which carry the handle-bars *g*. This gives great strength to the construction combined with lightness and permits the receptacle to be carried without 60 danger of breakage. The body of the receptacle is finished by covering the steel basket with cementitious material (Fig. 5).

The edge of the walls of the body of the receptacle is formed with an interior shoulder *h* upon which rests the cover *i*. The latter is made up of two wire shapes *b'*, *c'* between which is interposed a layer of cementitious material; and outside and inside of which are placed still other layers of like 70 material. The cover is formed with an opening *j* at each side of which is a ledge *k* upon which rests the glass cover *m*. Upon the cover *m* is placed the cement cover or lid *n* (Figs. 1, 2 and 3). The joint between the body of the cover and the lid *n* and glass plate *m* is sealed with cement, as is also the joint between the cover *i* and the body of the receptacle. The cover *i* is rounded as shown in Fig. 3. 80

My new receptacle is adapted for use not only as a casket proper but also as a box for the reception of the ordinary wooden casket heretofore used. The outside of my new receptacle may be finished with cloth or 85 in any other suitable manner to imitate in appearance the ordinary casket, heretofore in common use.

I claim:

A burial receptacle consisting of a plurality of wire shapes placed one within the other and separated by a layer of cementitious material; a basket comprising a frame which is substantially oblong in shape and attached to which are the upper ends of a 90 series of U-shaped bands, said wire shapes lying within said basket and being separated therefrom by a layer of cementitious material; and handle supports fastened to said basket at the junctions of the upper 95 ends of said U-shaped bands with said oblong frame, whereby rigidity of structure is obtained; the inside and outside of the receptacle being coated with cementitious material. 100

Signed at Erie, Neosho, Kansas, this 21st day of November, A. D., 1907, in the presence of the two undersigned witnesses.

JOHN H. TODD.
